UNITED STATES PATENT OFFICE.

CHARLES GILBERT HAWLEY, OF CHICAGO, ILLINOIS, ASSIGNOR, BY MESNE ASSIGNMENTS, TO CENTRIFIX CORPORATION, OF CLEVELAND, OHIO, A CORPORATION OF DELAWARE.

CENTRIFUGAL PROCESS AND APPARATUS.

Application filed November 28, 1924. Serial No. 752,717.

To all whom it may concern:

Be it known that I, CHARLES GILBERT HAWLEY, a citizen of the United States, residing at Chicago, Cook County, Illinois, have invented certain new and useful Improvements Entitled Centrifugal Processes and Apparatus, of which the following is a specification.

Though the apparatus herein disclosed is applicable in numerous industries and to various uses, this invention is primarily directed toward the purification of steam and like fluids and vapors before their release from the drums or chambers wherein the same are generated or stored.

This invention is a distinct improvement upon that disclosed by Joseph M. Schutz in application S. N. 690,861 filed February 5, 1924.

20 The purpose of the invention is to carry forward and render more certain of operation the Schutz centrifugal process and apparatus. The further and definite objects of the invention are detailed hereinafter.

25 My invention will be readily understood on reference to the drawings that form part of this specification and in which Fig. 1 illustrates the novel apparatus installed within the upper part of a pressure drum 1 devoted to the generation of steam or the like. Fig. 2 is a plan view of the apparatus partly in section on the line 2 and partly on the line 2^a of Fig 1. Fig. 3 is a vertical section on the line 3—3 of Fig. 2. Fig. 4 illustrates a modified arrangement of the protecting guard, but is otherwise like Fig. 3. Fig. 5 is a plan view resembling Fig. 2, but taken from Fig. 4, and Figs. 6 and 7 are enlarged details showing the means for positioning the side plates composing the guard.

40 Referring to Fig. 1, 1 represents the pressure drum, 2 the liquid level therein, 3 the outlet opening and 4 the nozzle proper. It will be understood that the off-take pipe is connected with the nozzle 4. But for the presence of the novel apparatus comprising this invention, the fluid or vapor leaving the chamber 5 could pass directly to the nozzle 4. Instead, this novel apparatus, though 45 composed of parts all of which are stationary, subjects the escaping fluid to a rapid whirling action, with the result that all substances heavier than the fluid are separated and discharged centrifugally. In its best

55 form the apparatus comprises the top casting 6, the bottom casting 7, the tangential tuyère ring 8, held between the two castings as by bolts 9, and, preferably, the enclosing hood or guard 10. The latter is either open at the top A as shown in Figs. 1, 2 and 3, or 60 is open at the bottom B, as illustrated by Figs. 4 and 5.

The top casting 6 has an upright portion 6^a, which meets the top of the drum 1, the same surrounding the outlet 3. It also has 65 the oppositely extending arms 6^b matching the bolts 11, by which the apparatus as a whole is supported from the top or roof of the drum 1. The body portion of the casting 6 is circular except for the presence of 70 the arms 6^a for the bolts 9. The casting contains the central opening 6^c of about the same size as the drum outlet 3.

75 The tuyère ring as here shown comprises a top ring 8^a and a larger bottom ring 8^b, joined by a plurality of vertical, tangentially positioned blades or vanes 8^c, best shown in Figs. 2 and 3. These parts may be integral, as though formed by a single casting or forging, or may comprise assembled 80 cast or forged sections. However formed, the tuyère ring is characterized by a generally cylindrical shape and by a bottom ring or portion 8^b, which contains a central opening of the same or slightly 85 greater size than the interior of the body or bladed portion of the tuyère ring. The upper part of the tuyère ring in every case is larger than the outlet opening 6^c, in consequence of which the member 6 presents the 90 annular overhanging shoulder or abutment 6^d, made familiar in above mentioned application S. N. 690,861.

95 The member 7 is a shallow circular bowl having at its periphery the tangential outlet 7^a. The boss 7^b which contains the outlet 7^a is a portion of the bottom casting 7. Into this I cast the pipe nipple 7^c, making the latter virtually an integral part of the member 7. The portion 8^b may be integral 100 with the upper margin of the bowl 7, but preferably the parts are distinct. That is, the ring 8^b is a separate member and is seated on an annular shoulder 7^d provided therefor in the top of the bowl member 7. In every case, according to this invention, the bowl is of so much greater diameter than the tuyère ring as to leave the underhang-

ing annular shoulder 8^{bx} and centrifugal expansion space 7^a, the latter comprising the peripheral portion of the bowl lying beneath the bottom of the tuyère ring. This centrifugal expansion space is of great importance as will presently appear.

The bowl 7 is characterized by a horizontal marginal extension 7e of polygonal, preferably square, shape. It is only substantially square, the edge being cambered, as clearly shown in Fig. 2, for a purpose about to be defined. The lower ends of the bolts 9 pass through this marginal or square extension at the top of the bowl.

As shown in Figs. 1, 2, 3, 6 and 7, at the middle points the edges of the part 7e contain projections 7^f. These serve to position and directly support the four plates 10—10 and 10'—10'. These rise from the square bottom 7e and therewith provide the tuyère ring with an enclosure which is open only at the top A. The vertical margins of the plates are held together by a plurality of short bolts 10^a. The top of the guard being flanged, is quite square. At the bottom the plates are sprung inward around the cambered edges of the part 7e, thus insuring tight joints. All joints of the hood or guard may be additionally packed if desired, though it is not necessary that they be actually water-tight.

The description of Figs. 1, 2 and 3 serves quite as well for Figs. 4 and 5, except that the top casting is the portion which is provided with the square web or portion 7^e. For as the guard 10^x in that case is open at the bottom B the top of the guard or hood must needs be closed, as by a portion 7^{ex}. The bottom member or bowl 7^x obviously is circular at the top except for the presence of the lugs 7^{al} for the bolts 9.

Special attention is called to the blades composing the body of the tangential tuyère ring. Their leading ends meet radii from the axis of the ring and the blades are at right angles thereto, and hence truly tangential. They may be positioned at slightly acute angles to the radii with no worse effect than a slight elongation of the tuyère ring. Anything approaching an obtuse angled arrangement is objectionable as such arrangements mark distinct loss of efficiency. Due to the described arrangement the fluid entering the tuyère ring is caused to impact surfaces which are tangential to the imaginary internal centrifugal surface of the tuyère ring. As a result, the first action which occurs is an impact separation of the heavier particles carried by the fluid and they are left or retained upon the inner surfaces of the blades. This effect is augmented by arranging the blades in overlapping relation as shown in Fig. 2. The main effect is nevertheless persistently retained in a blade construction like that in Fig. 5. The

tuyère structure of Fig. 2 forms and directs streams of fluid upon the tangentially inner surfaces of the tuyère blades.

The fluid entering the tuyère ring under pressure greater than that beyond the outlet 3 is limited by the wall of tangential blades and hence the stream as a whole takes on a rapid whirling motion within the tuyère ring. In consequence the impact collected substances are retained on the inner surfaces of the blades and tend to whirl along with the whirling body of fluid. Due to the presence of the annular abutment 6^a, the immediate escape of the fluid at the opening 3 is prevented, and in consequence a downward movement is instituted, there being a distinct downward cork-screw like motion within the tuyère ring which serves to deliver the collected substances into the bowl 7. The secret of success here lies in the annular expansion space 7^a, into which the collected substances are expandingly whirled. There, hidden or shielded from the main whirling flow of fluid, the collected substances, whether fluid or solids, are retained in separated condition and are whirlingly advanced to the discharge nozzle 7^a. By means of a pipe 12, the substances are either discharged into the body of fluid in the drum 1 or are discharged through the shell of the drum and thence taken care of by a collection pocket or an automatic discharge trap. Having been ridded of its burden of impurities or heavier substances, the whirling fluid within the tuyère ring reacts against the bottom of the bowl 7 and whirls upwardly at the axis of the bowl and thence escapes through the openings 6^a, 3 and 4.

In considering the above description of my novel process it will be understood either that the fluid is constantly supplied to the drum 1 or is generated or evolved therein, so that the stream of fluid may be considered as flowing constantly through the tuyères of the apparatus and through the outlet openings.

While the tuyère ring proper has been herein described in considerable detail, it is not intended to herein specifically claim that structure aside from the remainder of the construction presented.

Having thus described my invention, I claim as new and desire to secure by Letters Patent:

1. The herein described centrifugal process that consists in setting up within a flowing stream of fluid a localized whirling action in a region coaxial with and in direct axial communication with, but substantially perpendicular to, the outlet passage toward which the fluid moves, progressively causing a reactive whirling movement away from said outlet, collecting the heavier substances and expelling them peripherally out-

ward by centrifugal force, discharging them peripherally, and, finally permitting the inward reaction and escape of the purified fluid toward and along the extended axis of the outlet.

2. The herein described centrifugal fluid purifying device comprising a top member containing a central outlet in combination with a larger and generally tangential tuyère ring depending from said member, and, a still larger bowl member depending from said tuyère ring and characterized by an underhanging portion 8^{bx}, and said bowl portion having a peripheral discharge opening.

3. The herein described device comprising top and bottom members and an interposed tuyère ring, one of said members having a polygonal extension or web and a hood or guard comprising said web and a plurality

of side sheets attached to respective edges of said web.

4. The herein described centrifugal fluid purifying device comprising a flat member containing a central fluid outlet, in combination with a larger and generally tangential tuyère ring extending axially from said member and in axial alignment with said outlet, a still larger bowl member attached to the free end of said tuyère ring and characterized by an underhanging portion 8^{bx}, a fluid container enclosing said ring and bowl to direct the fluid into said ring, and, said bowl member having a peripheral discharge opening leading through the wall of said container.

In testimony whereof, I have hereunto set my hand this 24th day of November, A. D. 1924.

CHARLES GILBERT HAWLEY.
